UNITED STATES PATENT OFFICE.

ABRAHAM ANZELEWITZ, OF ANTWERP, BELGIUM.

NEEDLE-THREADING DEVICE FOR SEWING MACHINES.

1,107,873.

Specification of Letters Patent. Patented Aug. 18, 1914.

Application filed June 13, 1913. Serial No. 773,459.

To all whom it may concern:

Be it known that I, ABRAHAM ANZELEWITZ, a citizen of the United States of America, residing at 59 Rue St. Vincent, Antwerp, in the Kingdom of Belgium, have invented certain new and useful Improvements in Needle-Threading Devices for Sewing-Machines, of which the following is a specification.

10 This invention relates to devices for threading the needles of sewing machines of the kind in which a small hook carried by a movable arm secured to the presser-foot bar of the machine is adapted to be passed through the eye of the needle when the latter is stopped at a predetermined height to receive the thread and draw the latter through the eye on being withdrawn.

The main object of the present invention is 20 to provide a device of the above kind consisting of fewer parts than similar devices and being thus cheaper to manufacture and easier to operate. This object is attained mainly by so constructing the movable arm 25 carrying the hook that it can be shifted under the needle bar not only when the latter is in the required position to make the threader operative but also when it happens to be a little too low as frequently occurs by 30 reason of the difficulty of stopping it exactly at a predetermined point of its stroke.

A further object of the invention is to so construct the socket by means of which the movable arm is secured to the presser-bar 35 that the said socket may be fastened to a presser-foot of square or polygonal cross-section as well as to one of circular cross-section. This further object is accomplished by providing the inner wall of the socket with vertical angular equidistant grooves.

The accompanying drawing shows a preferred form of the device.

Figure 1 is a side view, Fig. 2 a front view, and Fig. 3 a plan view of the device 45 whereas Fig. 4 is a perspective view showing the same secured to the presser-foot bar of a sewing machine with the hook shifted through the needle hole.

In the said figures *a* is the hook carried by

a bent arm *b* provided with a socket *c* for 50 securing the device to the bar *f* of a presser foot *g*. The hook *a* is fastened in a slot of a small block *d* having two projecting wings *j* adapted to embrace the needle for the purpose of guiding and protecting the hook. 55 The said block *d* is secured to the lower end of the arm *b* by a screw *e* passed through a vertical slot *k* in the arm *b* for the purpose of adjusting the height of the block *d* and hook *a*. The upper horizontal portion of the 60 arm *b* is made of two parts *n, o*, capable of sliding on each other, one of which *n* is made with a slot *m* through which is passed a screw *l* screwed into the other part *o* in order that the length of the upper horizontal 65 portion of the arm may be adjusted. The front edge of the parts *n, o* is beveled or rounded so that, when the arm *b* is shifted for threading the needle, if the needle bar *i* is somewhat beneath the required height, the 70 same will be lifted up by the beveled edge of the parts *n, o* and will not prevent the arm *b* from passing under the needle bar for holding the latter in the required position.

Four vertical angular grooves *p* are 75 formed at equal distances from one another in the inner wall of the socket *c* for the purpose of allowing the latter to be fastened equally well upon square or round presser-foot bars.

What I claim and desire to secure by Letters Patent of the United States is:—

1. A hook-device for threading needles in 80 sewing machines comprising in combination with the presser-foot bar and needle bar of the machine, a hook, a bent support for said hook rotatably mounted upon said presser-foot bar the upper horizontal portion of said support being provided with a beveled front edge adapted to raise the needle bar when 85 said support is shifted under the latter for holding it in the proper position.

2. A hook device for threading needles in 90 sewing machines comprising in combination with the presser foot bar and needle bar of the machine, a hook, a block to which said hook is fastened, a socket provided with 95 internal vertical angular equidistant grooves

rotatably mounted upon said presser-foot bar and a bent arm depending from said socket and having an extensible horizontal portion with a beveled edge adapted to engage and raise the needle-bar and a vertical portion on which said block can be adjustably fixed in position.

In testimony whereof I affix my signature in presence of two witnesses.

ABRAHAM ANZELEWITZ.
